UNITED STATES PATENT OFFICE.

WILLIAM C. McCORMICK, OF GRANBURY, TEXAS.

SWITCH-LOCKING DEVICE.

1,297,200.

Specification of Letters Patent.

Patented Mar. 11, 1919.

Application filed May 15, 1918. Serial No. 234,740.

To all whom it may concern:

Be it known that I, WILLIAM C. McCORMICK, a citizen of the United States, residing at Granbury, in the county of Hood and 5 State of Texas, have invented new and useful Improvements in Switch-Locking Devices, of which the following is a specification.

This invention relates to switch locking devices, and the object is to provide a construction which shall be more efficient and more easily operated than many of the types of locking devices now in use.

A further object is to provide in connection with an operating arm carrying a hasp or the like, a resiliently mounted latch bolt designed to be engaged by the hasp for throwing the bolt to inoperative position, the latter then returning to operative position and passing through the hasp and retaining the latter in position for locking the switch.

A still further object is to provide means for retaining the latch both in inoperative position when desired.

With the foregoing and other objects in view, the invention consists in the novel construction, combination and arrangement of elements hereinafter described and claimed.

30 In the drawings—

Figure 1 is a view in vertical section.

Fig. 2 is a view in horizontal section.

Fig. 3 is an elevation with the cover for the casing inclosing the locking mechanism, 35 removed.

Fig. 4 is a view of the cover for the casing.

Fig. 5 shows a pivoted arm which operates through a slot in the cover, and retains 40 the locking bolt at times in inoperative position.

In carrying out my invention I provide a switch stand including any suitable supporting structure such as that shown at 10, carrying a table 12 provided with a slot 14 and with a central aperture 15, accommodating the rotatable member 16, carried by the rotatable element 17. The element last named is provided with a slot 18 having a beveled end portion 19 with which the beveled end 20 of the lever 21 comes into contact. The lever 21 is pivoted at 22, and is provided with a bail shaped member or hasp 24 engaged by the locking bolt, or latch bolt

35. One end of member 17 carries a plurality of upwardly extending supporting members 26 between which the free end of the lever 21 moves. These members 26 support a casing or the like shown at 28, serving to mount the locking members proper. The 60 casing is closed by means of a plate 30 provided with a key hole slot 31 and with a slot 32' through which a bolt retaining device passes, this retaining device holding the bolt in inoperative position when desired. 65

On one wall of the casing is a flat plate 32 having a beveled end 33 extending to the edge of the slot 34 in the adjacent wall of the casing. Opposite plate 32 I mount the latch bolt 35 having a cutaway portion 36 70 therein, the portion last named being engaged by the key to be inserted through slot 31. One end of the bolt constituting the engaging end is beveled at 37 and co-operates with the beveled portion of plate 32. The 75 end of the bolt is recessed at 39 and is engaged by coiled spring 40 for normally throwing the latch bolt into engaging position. Upon contact between the hasp and the beveled end of the bolt, the latter recedes permitting the hasp to pass between the bolt and plate 32, locking the switch arm.

In order to retain the locking bolt in inoperative position when desired, I provide 85 the latter with a notch 42 engaged by a pivoted member 43 mounted in ears 43' and extending through slot 32' of the casing plate or covering 30.

What is claimed is:

1. In a device of the class described, the combination with a switch stand, a rotatable member supported thereby, an arm pivotally mounted and adapted to rotate said member when in a given position, and means for locking the arm, said means last named including a hasp carried by the arm, a resiliently mounted locking bolt engaging the hasp, and means for retaining the locking bolt at times in inoperative position. 95

2. In a device of the class described, a rotatable member comprising an element of a switch operating device, an arm pivotally connected therewith and means for locking the arm, said means comprising a locking bolt having a beveled end portion, a plate positioned opposite said locking bolt and in alinement therewith and having a beveled 100

105

end coöperating with the corresponding end of the bolt, a casing for mounting the bolt and plate member, said casing being provided with a slot, means for resiliently retaining the bolt in position, means for retaining the bolt in inoperative position, and a hasp carried by the pivoted arm, said hasp

separating the bolt from the oppositely located plate to permit the hasp to pass the locking bolt, and the spring restoring the bolt to position for engaging the hasp and locking the arm.

In testimony whereof I affix my signature.
WILLIAM C. McCORMICK.
